Inventor.
Joseph M. McMaster,
for R. T. Osgood, Atty.

UNITED STATES PATENT OFFICE.

JOSEPH M. MCMASTER, OF ROCHESTER, NEW YORK.

TOY.

SPECIFICATION forming part of Letters Patent No. 447,411, dated March 3, 1891.

Application filed September 25, 1890. Serial No. 366,150. (No model.)

To all whom it may concern:

Be it known that I, JOSEPH M. MCMASTER, of Rochester, in the county of Monroe and State of New York, have invented a certain 5 new and useful Improvement in Toys; and I do hereby declare that the following is a full, clear, and exact description of the same, reference being had to the drawings accompanying this specification.

10 My invention is a new device or improvement in parlor-billiards.

In the invention two half-boxes are used as pockets, each having an opening in front. Three marbles are placed at stated distances 15 in advance of the boxes. A cue provided with a double elastic cord, string, or thread and having a rubber ball strung thereon is used as a shooting device. The game consists in shooting against the marbles and 20 driving them through the openings into the boxes.

The invention consists in the devices hereinafter described and claimed.

In the drawings, Figure 1 is a perspective 25 view of the two half boxes or pockets placed side by side with the openings downward and the marbles placed in position in advance of the boxes. Fig. 2 is a perspective view of the cue, the rubber ball being drawn back 30 and set in position for shooting. Fig. 3 is a diagram showing a sectional elevation of the devices shown in Fig. 1. Fig. 4 is a side elevation of the cue in position for shooting at the marbles in Fig. 3. Fig. 5 is a plan view 35 of the cue. Fig. 6 is a vertical section of the box when closed.

A A' indicate the two half boxes or pockets, each being provided with an opening or arch a, which, when the sections are separated and placed side by side, as shown in Fig. 1, stand downward and are in position to allow the marbles to be forced through the arch to the interior of the boxes or pockets. When not in use, these half-boxes are placed 40 one within the other, as shown in Fig. 6, forming a closed cube-shaped receptacle in which the marbles are kept ready for use.

B B B indicate the marbles, which, when the game is played, are placed in advance of

the half-sections of the box at any suitable 50 distances apart and about the distance of the width of the box in advance.

C is the cue consisting of a straight stick of proper length, smaller at one end than the other, as shown. To the small end is attached the two loose ends of a double elastic cord, string, or thread D, having a rubber ball E strung thereon, the cord passing through a hole in the ball. The ball is preferably of about the same size as one of the marbles. 60 The cue, elastic cord, and ball form the shooting device or gun.

In use the rubber ball E is drawn back over the base end of the cue, where it rests and retains its place, owing to the tension of the 65 cord, as shown in Figs. 2, 4, and 5. It will keep its place as long as desired. Aim is taken at one of the marbles, as shown in Fig. 4, and the shooting is done by slipping the ball over the end of the cue. It is found in 70 practice that accurate shooting can be done. The game consists in driving the marbles through the openings into the box. One alone counts one. If the ball strikes one and that drives in another, it counts two. If two balls 75 are driven in at one shot, it counts four. If all three are driven in at one shot, it is a sweep and wins the game without further scoring. The first player scoring ten points 80 wins the game. A miss gives the next player a chance.

Having described my invention, what I claim as new, and desire to secure by Letters Patent, is—

1. The combination of the half-boxes A A', 85 provided with the openings a a, the marbles B B B, set in advance of the half-boxes, and the shooting device consisting of the cue C, provided with the double elastic cord D and rubber ball E, as shown and described, and 90 for the purpose specified.

2. The shooting device consisting of the cue C, the double elastic cord D, attached to the small end thereof, and the rubber ball E, strung on the cord, the whole so arranged, as 95 herein described, that the device is set ready for use by drawing the ball over the base end of the cue, as specified.

3. In billiard toys, the combination of two
sectional pockets, each provided with an arch
or opening on one side and capable of being
shut together for convenience of transporta-
tion and storage, as herein shown and de-
scribed.

In witness whereof I have hereunto signed

my name in the presence of two subscribing
witnesses.

JOSEPH M. McMASTER.
